Application June 26, 1957, Serial No. 46,750

Term of patent 3½ years

(Cl. D33—6)

FIG. 1

FIG. 2

FIG. 3

Fig. 1 is a front perspective view of a dresser showing our new design.

Fig. 2 is an enlarged detail of a section taken on the line 2—2 of Fig. 1 showing the drawer molding.

Fig. 3 is a sectional view taken on the line 3—3 of Fig. 1.

The characterizing feature of the invention resides in the front panels of the dresser, an essential feature of each panel including the concave curve of the bordering frame in its relation to the re-entrant central panel as indicated in Fig. 3.

We claim:

The ornamental design for a dresser, as shown and described.
